UNITED STATES PATENT OFFICE

ERNEST C. HEAD, OF ROCHESTER, NEW YORK, ASSIGNOR TO GLEASON WORKS, OF ROCHESTER, NEW YORK, A CORPORATION OF NEW YORK

MACHINE FOR GENERATING GEARS

Application filed November 14, 1927, Serial No. 233,118. Renewed September 17, 1929.

The present invention relates to a machine for producing gears and particularly to a machine for generating bevel gears in a continuous indexing or hobbing process.

- 5 Among the objects of this invention are to provide a machine which will be fully automatic and which will be much faster in operation than machines heretofore constructed for the same purpose.
- 10 Other objects of the invention will be apparent hereinafter from the specification, when read in conjunction with the accompanying drawings, the novel features being pointed out in the claims appended hereto.
- 15 In the drawings:

Figure 1 is a side elevation of a machine constructed according to one embodiment of my invention;

Figure 2 is a plan view, partly in section, 20 of this machine;

Figure 3 is an end elevation of the machine looking from the right of Figure 1;

Figure 4 is a view partly in end elevation from the left of Figure 1 and partly in section on the line 4—4 of Figure 1;

Figure 5 is a view, partly in section, on a somewhat enlarged scale showing a detail of the fast and slow feed drive mechanism and the clutch controlling the operation of 25 the same;

Figure 6 is a section on the line 6—6 of Figure 5;

Figure 7 is a side elevation of the cam governing the feed and withdrawing movements 30 of the blank carrier and of the mechanism for shifting the speed control clutch;

Figure 8 is a section on the line 8—8 of Figure 7;

Figure 9 is a section on the line 9—9 of 35 Figure 7; and

Figure 10 is a diagrammatic view showing the general arrangement of the gearing controlling the operation of the various parts of the machine.

40 The present invention relates, in particular, to machines for generating tapered gears in a continuous cutting or hobbing process. In a machine of this character the tool and blank are rolled relatively to each other while 45 a continuous indexing rotation is imparted

to the blank, a predetermined timed relation being maintained between the tool mechanism and blank during the rolling movement.

In a machine of this character the blank is 55 completely cut during the roll of the machine in one direction. The machine is returned to initial or starting position preparatory to cutting a new gear, by reversing the direction of the rolling movement. For convenience, throughout this application, the 60 rolling movement during which cutting takes place will be referred to as the "rolling-generating" motion and the rolling movement during which the parts are returned to start- 65 ing position will be referred to as the "rolling-return" movement. It will be understood that these rolling movements may be imparted wholly to the blank, wholly to the tool or in part to the blank and in part to 70 the tool.

A machine of this character has the advantage that all of the teeth of the blank are 75 operated upon simultaneously with the consequence that any wear of the tool is distributed equally over all the teeth and that there is no danger of overheating the blank at any one point, as is possible when the teeth are completely generated successively. With a hobbing machine, moreover, complicated indexing mechanisms are avoided, the blank being indexed by a simple continuous rotary movement timed up with the tool movement.

Since the continuous relative rolling generating movement is coordinated with the continuous indexing movement of the blank, a motion is produced between the tool and blank corresponding exactly to that of a gear, as a crown gear, represented by the tool rolling continuously with the gear to be 80 cut. The relative rolling generating motion has, therefore, been used in the past to move the tool into and out of full depth cutting engagement with the blank, in addition to generating the profiles of the teeth of the 85 blank. This has meant that a sufficiently long rolling generating movement has been provided heretofore between the tool and blank to move the tool and blank into and out of engagement and to generate the teeth. With 90

this arrangement, however, the tool is doing no cutting at the beginning and at the end of the roll, the roll being employed at these times simply to move the tool and blank into and out of engagement. The purpose of the 5 present invention is to make this excessively long rolling action unnecessary and thereby speed up the operation of the machine. To this end, in a machine constructed according 10 to the preferred embodiment of this invention, the blank is positively fed into the tool during the first part of the rolling generating motion and is positively withdrawn relative to the tool by a bodily movement during 15 the last part of the rolling generating motion. In other words, instead of using a long rolling motion to feed the tool into the blank, to generate the teeth and to withdraw the tool from the blank, the blank is moved 20 bodily relative to the tool during the first and last parts of the rolling generating movement to feed the tool and blank into engagement and to withdraw them from engagement, respectively.

25 By the new method of operation, the actual rolling movement required is considerably lessened and the speed of the machine is accordingly increased.

In order to further reduce the time required for the operation of the machine, a 30 two speed drive is provided, by means of which the operation of the machine can be speeded up before and after the cutting operation, which necessarily takes place at a 35 relatively slow speed, so that at the beginning and during the last part of the rolling generating movement during the relative feed and withdrawing motions, respectively, the machine can be operated at a relatively fast speed.

40 In hobbing machines as heretofore constructed, it has been usual to reverse the machine at the end of the rolling generating movement by hand and throw in a fast speed 45 return drive. It is one of the purposes of the present invention, also, to provide means for automatically operating the reverse mechanism. This mechanism is so coordinated with the mechanism controlling the 50 speed of the machine that the direction of roll is reversed at predetermined points in the cycle and the rolling return movement is at a faster speed than the rolling generating movement during cutting.

55 In the preferred embodiment of this invention, the speed control mechanism is made adjustable relative to the mechanism controlling the direction of the rolling and continuous indexing motions and to the mechanism 60 producing the relative feed and withdrawing motions. By this arrangement, the speed control mechanism may be adjusted to speed up or slow down the operation of the machine at any predetermined points in the 65 cycle as may be deemed best in practise.

The invention is herein disclosed in connection with a machine for hobbing spiral or longitudinally curved tooth bevel gears with a taper hob. It will be understood, however, that the invention is not limited to machines employing this form of tool but may be used in connection with hobbing machines employing other forms of tools, as planing tools, face-mill hobbing cutters or cylindrical hobs and that, moreover, the invention 70 may be used in connection with the cutting of other forms of gears as, for instance, hypoid gears.

In the machine illustrated, the rotary taper hob is mounted upon a carrier or cradle which 75 rotates in one direction during the rolling generating movement and in the opposite direction during the rolling return movement. The gear blank is mounted upon a support or spindle and is given a combined generating and indexing rotation during the movement of the cradle in either direction. The blank spindle is mounted on a table which is 80 movable to feed the blank into cutting contact with the tool and to withdraw it from 85 engagement after the gear has been completely generated.

The motions of the cradle and blank spindle are governed from a continuously operating driving shaft which rotates a reversible 90 driven shaft through suitable reversing mechanism. A two speed drive is provided so that the driving shaft may be rotated selectively at a relatively fast speed or a relatively slow speed. By this arrangement, a rotary motion 95 may be imparted to the cradle and blank support alternately in opposite directions and at either a relatively fast or a relatively slow speed.

The feeding and withdrawing motions of 100 the blank support are effected by a cam which rotates continuously in one direction. The reversing mechanism is, also, controlled by a cam which rotates continuously in one direction. The two cams are preferably mounted 105 on the same shaft and this cam shaft carries preferably, also, the device controlling the speed drive of the driving shaft above referred to. The speed control device is preferably made adjustable relative to the two 110 cams and the cams and speed control are preferably so coordinated that the blank is fed toward the hob partly during the last part of the rolling return movement and partly 115 during the first part of the rolling generating movement, during which time the machine will be operated at a relatively high speed, that the machine will be driven at a relatively slow speed during cutting and that the blank will be withdrawn from engagement with the hob partly during the last part 120 of the rolling generating motion and partly during the first part of the rolling return movement. The reversing mechanism which controls the direction of the roll is actuated 125

automatically to permit of such a cycle. The cam which controls the feed and withdrawing motions of the work table is preferably driven continuously in one direction from the driving shaft, whereby by a suitable adjustment of the devices controlling the speed of the driving shaft, it will be possible to use the same cam to produce the feed and withdrawal movements at different times in the cycle of operation of the machine as may be desired in cutting different gears.

Referring now to the drawings: 10 indicates the base or frame of the machine. The bed or frame 10 is provided with ways on which are guided the tracks 11 of the cradle 12 on which the tool mechanism is mounted. The bed or frame serves as a support, also, for the work carrier or table 14. The tool, which in the mechanism illustrated is a taper hob H is mounted upon a spindle 15 journaled in a tool carrier 16 (Fig. 2). Preferably, the hob is supported at its outer end by a tailstock 17 carried by a bracket 18 which is adjustable on the tool carrier 16 to permit of supporting hobs of different lengths. For the sake of clearness in illustration the tailstock has been omitted in Figure 1. The angular adjustment of the tool carrier 16 is effected about the axis of a vertical shaft 20 (Fig. 1) and is for the purpose of positioning the hob in the proper tangential relation to the blank. The carrier 16 may be secured in any adjusted position by means of the bolt 21 (Fig. 2) which engages in a curved slot formed in the slide 22 concentric with the axis of the shaft 20.

The tool carrier 16 is supported on the swiveling head 19 which is angularly adjustable about the axis of the shaft 53 (Fig. 2) to permit adjusting the hob to cut gears of either right or left hand. The head 19 can be secured in any adjusted position, as by means of T-bolts (not shown), on the slide 22 which is horizontally adjustable upon a vertical slide 23 and which may be secured in any adjusted position by means of the bolts 24. The vertical slide 23 is vertically adjustable upon the upright or standard 26 and this upright or standard 26 is in turn horizontally adjustable upon the cradle 12 in a direction at right angles to the direction of adjustment of the slide 22. The bolts 27 serve to hold the vertical slide 23 in adjusted position, while the bolts 28 serve to secure standard or upright 26 in any position of adjustment upon the cradle. The various adjustments described, which may be effected by hand or in any usual or suitable manner are for the purpose of positioning the hob H in proper relation to the gear blank to be cut. The work carrier or table 14 is angularly adjustable upon the bed or frame 10 for positioning the blank in the correct tangential relation to the hob. This adjustment can be effected by rotating a pinion (not shown)

carried by the blank carrier in engagement with a rack member 30 (Figs. 2 and 3). This is a usual adjustment in bevel gear cutting machines. The blank carrier or table can be secured in any adjusted position to the rack member 30 by means of bolts which engage in a T-slot 31 formed in this member. Slidably adjustable on the swinging base or work table 14 is the work head column 33 which is movable on the base or table 14 in a horizontal direction to permit adjusting the cone apex of the blank to the correct position. Mounted for vertical adjustment upon the work head column 33 is the work head 35 in which the blank spindle 36 is journaled. The vertical adjustment of the work head permits of positioning the blank spindle with the axis of the blank either intersecting the axis of the cradle or offset therefrom any desired amount. The work head column 33 may be secured in any adjusted position on the work table 14 by means of the bolts 37 and the work head 35 can be secured in any adjusted position upon the column by means of the bolts 38. The various adjustments of the blank spindle may be effected by hand or in any usual or suitable manner.

During the operation of the machine, the hob is rotated continuously on its axis being driven from the motor 40 (Figs. 1, 2 and 10) through the bevel gears 41, 42, the spur gears 43, 44, the shaft 45 the miter gears 46, 47, the miter gears 48, 49, the swinging shaft 50, the miter gears 51, 52, the shaft 53, the miter gear 54 which has a splined connection with said shaft, the miter gear 55 meshing therewith, the speed change gears 57, 58 and 59 the bevel pinion 60 and the bevel gear 61 which is secured to the spindle 15 to which the hob arbor is secured.

The blank is rotated continuously on its axis in timed relation with the hob rotation. This continuous rotary movement acts to continuously index the blank during cutting so that all the teeth of the blank are completed simultaneously. The continuous rotation is effected from the shaft 45 through the gears 65, 66 and 67 (Figs. 1, 2 and 10), the bevel gears 68 and 69, the shaft 70, the miter gears 71 and 72, the shaft 73, the differential gears 74 connecting this shaft with the shaft 75, the shaft 75 (see also Fig. 4), the miter gears 76 and 77, the vertical shaft 78, the miter gears 79 and 80, the diagonal shaft 81, the miter gears 82 and 83, the horizontal telescoping shaft 84, which is journaled in the work table 14 and in a bracket 85 secured to the work head column 33, the index change gears 87, 88 and 89, the shaft 90 which is journaled in the work head 35, the miter gears 91 and 92, the worm shaft 94 journaled in the work head, the worm 95 secured to said shaft and the worm wheel 96 which meshes therewith and is secured to the blank spindle 36.

For the purpose of generating the tooth

- profiles of the gear to be cut a relative rolling motion is imparted between the hob and blank. This relative rolling motion is effected in the machine illustrated by rotating 5 the cradle on its axis and simultaneously imparting to the blank a rotary motion which combined with the cradle movement produces a relative movement between the hob and blank corresponding to that of a gear rolling 10 on the basic gear represented by the hob.
- 10 The mechanism for producing the rotary motion of the cradle and the generating rotation of the blank will now be described. Mounted upon the shaft 45 already referred to is a 15 miter gear 100 which meshes with a miter gear 101 upon a shaft 102 which is journaled in the base or frame of the machine. This shaft 102 carries adjacent its outer end a spur gear 103 which meshes with a spur gear 104 20 that is secured to a shaft 105 which is also journaled in the base or frame of the machine. The shaft 105 is adapted to drive a shaft 106 at either a relatively fast or a relatively slow speed. The fast speed drive is effected 25 through the spur gears 108, 109 and 110. The slow speed drive is effected through the bevel gears 111 and 112, the worm shaft 113 which is journaled in the frame of the machine, the worm 114 and the worm wheel 115 30 which meshes with the worm and is driven thereby. The spur gear 110 and the worm wheel 115 are both rotatably mounted upon the shaft 106 and may be selectively and alternately connected with the shaft 106 by 35 means of the slidable clutch member 118 which has a splined connection with the shaft 106 and which is provided with clutch teeth at either end adapted to engage selectively the clutch teeth formed upon the adjacent ends 40 of the sleeves of the gears 110 and 115. As will be obvious, by engagement of the clutch member 118 with the gear 110 or the gear 115 the shaft 106 may be driven either at a relatively fast or a relatively slow speed.
- 45 The shaft 106 drives a reversible shaft 120 through a reversing mechanism which may be of any usual or suitable character. The reversing mechanism illustrated is described in the U. S. patent to Gleason et al., No. 50 1,203,608, November 7, 1916 and reference may be had to that patent for a more complete description of the mechanism herein shown. Suffice it to say that the shaft 120 may be driven from the shaft 106 in one direction or the other, alternately, through the spur gears 121 and 122 or through the spur gear 124, the idler 125 and the spur gear 126. 55 The reversible shaft 120 carries adjacent its outer end a spur gear 127 which meshes with a spur gear 128 that is secured to a shaft 129 which is journaled in the frame or base of the machine. The shaft 129 carries two bevel gears 130 and 131. The bevel gear 131 meshes with a bevel gear 132 upon a transverse worm shaft 133. This worm shaft 133

is journaled in the base or frame of the machine and carries a worm 134 that meshes with and drives a worm wheel segment 135 which is secured to the cradle 12. By the means just described a rotary motion is imparted to the cradle in either direction depending upon the direction of rotation of the reversible shaft 120 and at a relatively slow or a relatively fast speed depending upon the position of the clutch member 118.

70 The bevel gear 130 already referred to meshes with a bevel gear 137 on a shaft 138 which carries adjacent its outer end a spur gear 139. The spur gear 139 drives through the spur gears 140, 141, and 142, the spur gear 143 which is secured to the housing 145 of the differential gears 74. The differential acts to combine the continuous indexing motion with the generating motion and impart these combined motions through the shaft 75 and the gearing already described to the worm wheel 96 and the blank spindle.

75 From what has been said, it will be seen that the generating motion may be imparted to the cradle and to the blank spindle in either direction and at either a fast or a slow speed. The means governing the speed of the driving shaft 106, the means for controlling the reversing mechanism and the means governing the feed and withdrawing motions of the 80 blank table will now be described.

85 Mounted on the driving shaft 106 adjacent one end is a spur gear 150 which drives through the idler 151 and the gear 152, the worm shaft 154 which is journaled in the frame of the machine. This worm shaft 154 carries a worm 155 which meshes with and drives a worm wheel 156 upon a cam shaft 157 that is journaled in the frame.

90 Mounted on the cam shaft 157 are two cams 160 and 161. The cam 160 controls the reversing mechanism through the lever 162 and slide 163 which is operated by this lever to operatively engage the gear 122 or the gear 126 with the reversible shaft 120. The lever 110 162 is pivoted on a bracket arm 164 which is secured to the frame of the machine and carries intermediate its end a roller 165 which travels in the cam slot formed in the face of the cam member 160.

105 The cam member 161 governs the feed and withdrawing movements of the swinging base or work table 14. The work table is angularly adjusted on and secured to the rack member 30 and this rack member 30 may be oscillated about the axis of the vertical shaft 78 under actuation of the cam 161 to feed the blank into and withdraw it from engagement with the hob. The cam 161 is connected to the rack member 30 through instrumentalities similar to those shown in Patent No. 1,203,608 above referred to. These instrumentalities comprise generally a swinging arm 170 connected to the rack member and carrying a roller 172 which engages in the 110 120 125 transverse worm shaft 133. This worm shaft 133

peripheral cam groove of the cam member 161.

Secured to one face of the cam member 161 are a pair of lugs 173 and 174. These lugs 5 are adjustable about the axis of the cam and may be secured in any adjusted position by means of bolts 175 and 176 which engage in a circular T-slot formed in the front face of the cam coaxial with the axis of the cam shaft. Journaled in the frame and extending parallel to the cam shaft 157 is a rock shaft 180 (Figs. 2 and 3). This rock shaft carries a segment 181 which meshes with a segment 182 rotatably mounted upon a stud 183 which 10 is secured in a bracket 185 that is fastened to the frame. Secured to the segment 181 is an arm 186 that carries a roller 187. Secured to the segment 182 is an arm 188 that carries a roller 189. The roller 189 carried by the 15 arm 188 is engaged by the lug 173, while the roller 187 carried by the arm 186 is engaged by the lug 174 during the rotation of the cam shaft 157. The arm 188 is bent laterally at one end and the lug 174 is cut away, as 20 shown in Figures 8 and 9, so that the roller 189 and arm 188 will clear the lug 174 during the rotation of the cam 161. From the arrangement described, it will be seen that as 25 the cam rotates the lugs 173 and 174 will alternately engage the rollers 189 and 187 thus alternately rocking the arms 186 and 188 to rock the shaft 180 alternately in opposite directions through the gear segments 181 and 182.

Secured to the rock shaft 180 at its outer end is an arm 190 which is connected by a link 191 (Figs. 1, 5 and 6) with an arm 192 which is oscillatable upon a stud 193 that is mounted in the frame. The arm 192 carries a pin 195 which travels in an elongated slot 196 in the arm 197 of the yoke member 198. The yoke member 198 is oscillatable on the stud 193 and is connected to the clutch member 118 in the usual manner. The arm 192 is furcated to receive the link 191 and a roller 199 which is mounted upon the pin 195. Mounted in a socket in the base is a spring pressed plunger 200, the head of which is of truncated V-shape. This plunger 200 engages the roller 199.

When the shaft 180 is rocked the arm 192 is oscillated in one or the other direction about the stud 193 causing the roller 199 to ride on the plunger 200 and the pin 195 to travel in the slot 196 of the yoke member 198. When the pin has passed neutral position in traveling in the slot 196 from left to right or right to left the plunger 200 will give it a quick thrust which will throw the arm 197 of the yoke member about the stud 193 and shift the clutch member 118 to disengage the slow or fast feed drive, as the case may be, and engage the other drive.

The operation of the machine will be obvious from the preceding description but may

be briefly summed up here. The upright 26 is adjusted on the cradle 12, the vertical slide 23 is adjusted on the standard 26, the head 19 is swivelled about the axis of the shaft 53 and the tool carrier 16 is angularly adjusted about the axis of the vertical shaft 20 to secure the desired offset of the hob axis from the axis of the cradle and to bring the hob apex into the correct position. By a proper angular adjustment of the head 19, it is possible to 70 position the hob for cutting right or left hand spiral teeth, as may be desired. The horizontal slide 22 is adjusted on the vertical slide 23 to bring the hob into the correct tangential plane. The work table or swinging 75 base 14 is adjusted on the rack member 30 to bring the blank into correct tangential relation with the hob, the work head column 33 is adjusted upon the base or table 14 to bring the cone apex of the blank into the correct 80 position; and the work head 35 is adjusted vertically upon the column 33 to position the blank axis in any desired offset relation to the axis of the cradle or with the blank axis intersecting the axis of the cradle. The lugs 85 173 and 174 (Fig. 7) are also adjusted upon the cam 161 to actuate the clutch shifting mechanism to change the speed of the machine at the desired points in the cycle of operation. The motor 40 may then be started. 90 The hob is rotated continuously on its axis through the gearing already described. Simultaneously the blank is given a combined 95 indexing and generating rotation and the cradle is rotated in one or other direction 100 upon its axis. The cam shaft 157 is driven continuously in the same direction through the gearing described and the cam 161 will operate the reverse mechanism at the desired points in the cycle, while the cam 161 will 105 swing the base or table 14 to feed the blank positively into the hob or withdraw it from engagement with the hob.

Means is preferably provided for stopping 110 the machine automatically on the rolling return movement when the machine has reached the starting position. In the machine illustrated, this automatic stopping mechanism comprises a dog 205 (Fig. 4) carried by the cradle which is adapted to engage a star wheel 115 206 which is rotatably mounted upon the frame. The dog 205 is so constructed as to pass idly over the star wheel during movement of the cradle on one direction and to engage and rotate the star wheel through the 120 angle of one tooth on the return roll of the cradle. The rotation of the star wheel under actuation of the dog brings a tooth of the star wheel into engagement with the switch 307, disengaging the switch and stopping the 125 motor and the machine. The star wheel 206 is resiliently held against movement except when actuated by the dog 205 by a spring pressed plunger 208 which is housed in the frame. The machine is thus stopped auto- 130

matically at a predetermined point on the return roll of the cradle. When the motor 40 is started, then, the machine will complete the return rolling movement, the reverse mechanism will be operated, the cradle and blank will be rolled in the opposite direction for cutting and after the blank has been cut, the machine will be again reversed and the parts returned to initial or starting position when the machine will be automatically stopped by the mechanism just described.

Preferably the lugs 173 and 174 will be so adjusted on the cam 161 that when the machine is started the driving shaft 106 will be operated at a fast speed, that during this fast speed movement and during the last part of the return roll and the first part of the rolling generating movement, the blank will be fed into engagement with the hob, that after the blank has been fed into the proper depth the speed clutch 118 will be shifted and the machine operated at a relatively slow speed for cutting, that after the cutting operation has been completed the slow speed drive will be disengaged and the fast speed drive again thrown in, that during the last part of the rolling generating movement the now completed gear will be partly withdrawn from engagement with the hob, that this withdrawing motion will be completed on the return roll and that the return roll will be at the relatively fast speed also.

While the invention has been described in connection with a particular embodiment, it is to be understood that the invention is capable of various further modifications and uses without departing from its scope and that this application is intended to cover any adaptations, uses or embodiments of the invention following, in general, the principles of the invention and including such departures from the present disclosure as come within known or customary practise in the gear art and as may be applied to the essential features hereinbefore set forth and as fall within the scope of the invention or the limits of the appended claims.

Having thus described my invention, what I claim is:

1. In a gear generating machine, a blank support, a tool mechanism, means for effecting a continuous relative rolling generating movement of the tool and blank in one direction and a continuous relative rolling return movement in the opposite direction, means for imparting a continuous rotary motion to the blank during the rolling movement in either direction, and means acting automatically to impart a relative depthwise feed movement between the tool and blank during the first part of said rolling generating movement to move the tool and blank into engagement.

2. In a gear generating machine, a blank support, a tool mechanism, means for effect-

ing a continuous relative rolling generating movement of tool and blank in one direction and a continuous relative rolling return movement in the opposite direction, means for producing a continuous rotary movement of the blank during the rolling motion in either direction, and means acting automatically to effect a positive relative withdrawing movement between tool and blank during the latter part of said rolling generating movement.

3. In a gear generating machine, a blank support, a tool mechanism, means for effecting a continuous relative rolling generating movement of tool and blank in one direction and a continuous relative rolling return movement in the opposite direction, means for producing a continuous rotary motion of the blank during the rolling movement in either direction, and means acting automatically to effect a positive movement of tool and blank into and out of engagement during the first and latter parts of said rolling generating movement, respectively.

4. In a gear generating machine, a blank support, a tool mechanism, means for effecting a continuous relative rolling generating movement of tool and blank in one direction and a continuous relative rolling return movement in the opposite direction, means for imparting a continuous rotary motion to the blank during the rolling movement in either direction, and means acting automatically to commence a relative depthwise feed movement between tool and blank during said rolling return movement and to complete said feed movement during the first part of said rolling generating movement.

5. In a gear generating machine, a blank support, a tool mechanism, means for effecting a continuous relative rolling generating movement of tool and blank in one direction and a continuous relative rolling return movement in the opposite direction, means for imparting a continuous rotary motion to the blank during the rolling movement in either direction, and means acting automatically to commence a positive relative withdrawing movement between tool and blank during the latter part of said rolling generating motion and to complete said relative withdrawing movement during the first part of said rolling return motion.

6. In a gear generating machine, a blank support, a tool mechanism, means for effecting a continuous relative rolling generating movement of tool and blank in one direction and a continuous relative rolling return movement in the opposite direction, means for imparting a continuous rotary motion to the blank during the rolling movement in either direction, and means acting automatically to complete a relative depthwise feed movement between tool and blank and to commence a positive relative withdrawing

- movement between tool and blank during the first and latter parts of said rolling generating movement, respectively.
7. In a gear generating machine, a blank support, a tool mechanism, means for effecting a continuous relative rolling generating movement of tool and blank in one direction and a continuous relative rolling return movement in the opposite direction, means for imparting a continuous rotary motion to the blank during the rolling movement in either direction, and means acting automatically to commence a relative depthwise feed movement between tool and blank during the rolling return movement and to complete said feed movement during the first part of said rolling generating movement, and to commence a positive relative withdrawing movement between tool and blank during the latter part of said rolling generating movement and to complete said relative withdrawing movement during the first part of said rolling return motion.
8. In a gear generating machine, a blank support, a tool mechanism, means for effecting a continuous relative rolling generating movement of tool and blank in one direction and a continuous relative rolling return movement in the opposite direction, means for imparting a continuous rotary motion to the blank during the rolling movement in either direction, a slow speed drive and a fast speed drive adapted to alternately actuate said first named means, said slow speed drive being operable during cutting and means acting automatically to disengage the slow speed drive and to engage the fast speed drive after the cutting operation has been completed to effect the return movement at a relatively fast speed.
9. In a gear generating machine, a blank support, a tool, mechanism for effecting a continuous relative rolling generating movement of tool and blank in one direction and a continuous relative rolling return movement in the opposite direction, means for producing a continuous rotary motion of the blank during the rolling movement in either direction, a relatively slow speed and a relatively fast speed drive for alternately driving said first named mechanism, and means automatically controlling said drives to operate said mechanism at a relatively fast speed during the first part of said rolling generating motion, while the tool and blank are out of engagement, and to operate said mechanism at a relatively slow speed during the cutting operation.
10. In a gear generating machine, a blank support, a tool, mechanism for effecting a continuous relative rolling generating movement of tool and blank in one direction and a continuous relative rolling return movement of tool and blank in the opposite direction, means for effecting a continuous ro-
- tary motion of the blank during the rolling movement in either direction, a slow speed and a fast speed drive for alternately driving said first named mechanism, and means automatically controlling said drives to operate said mechanism at a relatively fast speed during the first and last parts of said relative rolling generating movement, while the tool and blank are being moved into and out of engagement, and to operate said mechanism at a relatively slow speed during the cutting operation.
11. In a gear generating machine, a blank support, a tool, mechanism for effecting a relative rolling generating movement between the tool and blank in one direction and a relative rolling return movement in the opposite direction, means for simultaneously producing a continuous rotary motion of the blank during the rolling movement in either direction, means acting automatically to impart a relative depthwise feed movement between the tool and blank during the first part of said rolling generating movement to move the tool and blank into engagement, and means for actuating said first named mechanism at a relatively fast speed during said feed movement and at a relatively slow speed during the actual cutting operation.
12. In a gear generating machine, a blank support, a tool, mechanism for effecting a relative rolling generating movement between the tool and blank in one direction and a relative rolling return movement in the opposite direction, means for simultaneously producing a continuous rotary motion of the blank during the rolling movement in either direction, means acting automatically to effect a positive relative withdrawing movement between tool and blank during the latter part of said rolling generating movement, and means for actuating said first named mechanism, at a relatively slow speed during the cutting operation and at a relatively fast speed during the relative withdrawing movement.
13. In a gear generating machine, a blank support, a tool, mechanism for effecting a relative rolling generating movement between the tool and blank in one direction and a relative rolling return movement in the opposite direction, means for simultaneously producing a continuous rotary motion of the blank during the rolling movement in either direction, means acting automatically to effect a positive movement of tool and blank into and out of engagement during the first and latter parts of said rolling generating movement, and means for actuating said first named mechanism at a relatively slow speed during cutting and at a relatively fast speed during the movement of the tool and blank into and out of engagement.
14. In a gear generating machine, a blank

- support, a tool, mechanism for effecting a relative rolling generating movement between the tool and blank in one direction and a relative rolling return movement in the opposite direction, means for simultaneously producing a continuous rotary motion of the blank during the rolling movement in either direction, means acting automatically to commence a positive relative withdrawing movement of tool and blank during the latter part of the rolling generating motion and to complete said relative withdrawing motion during the first part of said rolling return movement, and means for automatically actuating said first named mechanism at a relatively slow speed during cutting and at a relatively fast speed during said relative withdrawing motion and said rolling return movement.
15. In a gear cutting machine, a blank support, a tool, mechanism for effecting a relative rolling generating movement between the tool and blank in one direction and a relative rolling return movement in the opposite direction, means for simultaneously producing a continuous rotary motion of the blank during the rolling movement in either direction, means acting automatically to commence a relative withdrawing movement between tool and blank and to complete a relative depthwise feeding movement of tool and blank at the latter and first parts of said relative rolling generating movements, respectively, and means for automatically actuating said first named mechanism at a relatively fast speed during said withdrawing and feed motions and at a relatively slow speed during cutting.
20. 16. In a gear generating machine, a blank support, a tool, mechanism for effecting a relative rolling generating movement between the tool and blank in one direction and a relative rolling return movement in the opposite direction, means for simultaneously producing a continuous rotary motion of the blank during the rolling movement in either direction, means acting automatically to commence a positive relative depthwise feed motion between the tool and blank during the latter part of said rolling return movement and to complete said relative feed movement during the first part of the rolling generating motion and means for automatically actuating said first named mechanism at a relatively fast speed during said feed movement and at a relatively slow speed during cutting.
25. 17. In a gear generating machine, a blank support, a tool, mechanism for effecting a relative rolling generating movement between the tool and blank in one direction and a relative rolling return movement in the opposite direction, means for simultaneously producing a continuous rotary motion of the blank during the rolling movement in either direction, means for effecting positive relative withdrawing and feed movements between tool and blank, means for automatically reversing the direction of the relative roll-
30. 35. to commence a positive relative withdrawing movement between the tool and blank during the latter part of said rolling generating motion, to complete said withdrawing movement during the first part of the rolling return motion, to commence a relative feeding movement during the latter part of the rolling return motion, and to complete said feeding movement during the first part of the rolling generating motion, and means for automatically actuating said first named mechanism at a relatively fast speed during said withdrawing and feed movements and throughout said rolling return movement and for actuating said mechanism at a relatively slow speed during the cutting operation.

18. In a gear generating machine, a blank support, a tool, mechanism for effecting a relative rolling generating movement between the tool and blank in one direction and a relative rolling return movement in the opposite direction, driving means for actuating said mechanism alternately at a relatively fast speed and a relatively slow speed, means for automatically effecting a positive relative withdrawing and a positive relative feed movement between the tool and blank and adjustable means for automatically controlling said driving means to actuate said first named mechanism alternately at fast and slow speeds at predetermined points in the cycle of operation of the machine.
19. In a gear generating machine, a blank support, a tool, mechanism for effecting a relative rolling generating movement between the tool and blank in one direction and a relative rolling return movement in the opposite direction, means for simultaneously producing a continuous rotary motion of the blank during the rolling movement in either direction, driving means for actuating said first named mechanism at a relatively fast speed and at a relatively slow speed, means for automatically reversing the direction of the relative rolling movement, and adjustable means for controlling said driving means to actuate said mechanism at fast and slow speeds alternately at predetermined points in the cycle of operation of the machine.
20. In a gear generating machine, a blank support, a tool, mechanism for effecting a relative rolling generating movement between the tool and blank in one direction and a relative rolling return movement in the opposite direction, means for simultaneously producing a continuous rotary motion of the blank during the rolling movement in either direction, means for effecting positive relative withdrawing and feed movements between tool and blank, means for automatically reversing the direction of the relative roll-

- ing movement, and means, adjustable relative to the reversing mechanism and the mechanism for effecting withdrawing and feed movements of tool and blank, for automatically controlling the driving means to alternately actuate said first named mechanism at slow and fast speeds at predetermined points in the cycle of operation of the machine.
21. In a gear generating machine, a blank support, a tool, mechanism for effecting a relatively rolling generating movement between the tool and blank in one direction and a relative rolling return movement in the opposite direction, means for simultaneously producing a continuous rotary motion of the blank during the rolling movement in either direction, reversing mechanism for automatically controlling the direction of operation of the first named mechanism, driving means for actuating said first named mechanism at a relatively slow speed and at a relatively fast speed, and means for automatically controlling said driving means to effect the rolling generating movement at a relatively slow speed during cutting and the rolling return movement at a relatively fast speed.
22. In a gear generating machine, a blank support, a tool, mechanism for effecting a relative rolling generating movement between the tool and blank in one direction and a relative rolling return movement in the opposite direction, means for simultaneously producing a continuous rotary motion of the blank during the rolling movement in either direction, reversing mechanism for controlling the direction of operation of the first named mechanism, gearing for automatically driving said first named mechanism at a relatively fast speed and at a relatively slow speed, means for automatically controlling said gearing to actuate the first named mechanism at a relatively slow speed during cutting and at a relatively fast speed during the rolling return movement, and means for automatically stopping the machine when it has returned to starting position.
23. In a machine for generating gears, a blank support, a tool, mechanism for imparting a relative rolling movement between the tool and blank in opposite direction, means for simultaneously producing a continuous rotary motion of the blank during the roll in either direction, the cutting operation taking place during the rolling movement in one direction and the parts being returned to starting position during the rolling movement in the opposite direction, and means for driving said mechanism at a relatively slow speed during cutting and at a relatively fast speed during the return movement.
24. In a machine for generating gears, a blank support, a tool, mechanism for imparting a relative rolling movement between the tool and blank in opposite directions, means for simultaneously producing a continuous rotary movement of the blank during the roll in either direction, the cutting operation taking place during the rolling movement in one direction and the parts being returned to starting position during the rolling movement in the opposite direction, reversing mechanism for automatically controlling the direction of the relative rolling movement, and means for driving said first named mechanism at a slow speed during cutting and at a relatively fast speed during the return movement.
25. In a machine for generating gears, a blank support, a tool support, one of which is movable toward and from the other, a tool mounted on said tool support, a movable cradle upon which one of said supports is mounted, a driving shaft turning continuously in one direction, a driven shaft operatively connected with the driving shaft through reversing mechanism whereby the driven shaft rotates alternately in opposite directions, gearing connecting said reversible shaft with the blank support and cradle, means for simultaneously imparting to the blank a continuous indexing motion, gearing for rotating the driving shaft at a relatively slow speed and at a relatively fast speed and means for automatically controlling the operative engagement of said last named gearing with said driving shaft.
26. In a machine for generating gears, a blank support, a tool support, one of which is movable from and toward the other, a tool mounted on the tool support, a movable carrier upon which one of said supports is mounted, a driving shaft turning continuously in one direction, a driven shaft operatively connected with said driving shaft through reversing mechanism whereby the driven shaft rotates alternately in opposite directions, gearing connecting said reversible shaft with the blank support and cradle, means for simultaneously imparting to the blank a continuous indexing motion, gearing for rotating the driving shaft at a relatively fast speed and at a relatively slow speed, means for automatically controlling the operative engagement of said last named gearing with said driving shaft and means for automatically effecting relative withdrawing and feed movements between the tool and blank at predetermined points in the cycle of operation of the machine.
27. In a machine for generating gears, a blank support, a tool support, one of which is movable toward and from the other, a tool mounted on the tool support, a movable cradle upon which one of said supports is mounted, a driving shaft turning continuously in one direction, a driven shaft operatively connected therewith through reversing mechanism whereby the driven shaft rotates alternately in opposite directions, gear-

ing connecting said reversible shaft with the blank support and cradle, means for simultaneously imparting to the blank a continuous indexing motion, gearing for rotating the driving shaft alternately at a relatively fast speed and at a relatively slow speed, a cam shaft driven from said driving shaft, a cam mounted thereon for effecting a relative movement of tool and blank toward and from each other, means on said cam shaft for actuating said reversing mechanism, and means adjustably mounted on said cam shaft for controlling the operative engagement of said speed gearing with said driving shaft.

28. In a machine for generating gears, a blank support, a tool support, one of which is movable toward and from the other, a tool mounted on the tool support, a movable cradle upon which one of said supports is mounted, a train of gearing for imparting rotary movement to the blank support and cradle comprising a drive shaft, a driven shaft operatively connected therewith through reversing mechanism whereby the driven shaft rotates alternately in opposite directions, and means connecting said reversible shaft with the blank support and cradle, means for simultaneously imparting to the blank a continuous indexing motion, gearing for alternately driving one element of said train at a relatively slow speed and at a relatively fast speed, a clutch mechanism controlling alternate connection of said speed gearing with said element, a cam shaft driven from said driving shaft, a cam, mounted thereon, for effecting a relative movement between the tool and blank toward and from each other, means on said cam shaft for operating said reversing mechanism, and a member adjustably mounted on said cam shaft for shifting said clutch.

29. In a machine for generating gears, a blank support, a tool support, one of which is movable toward and from the other, a tool mounted on said tool support, a movable cradle upon which one of said supports is mounted, a train of gearing for imparting rotary movement to the cradle and blank support comprising a drive shaft, a driven shaft operatively connected therewith through reversing mechanism whereby the driven shaft rotates alternately in opposite directions and means operatively connecting said reversible shaft with the blank support and cradle, means for simultaneously imparting to the blank a continuous indexing motion, gearing for driving one element of said train alternately at a relatively slow speed and at a relatively fast speed, a clutch mechanism controlling the alternate connection of said speed gearing, with said element a cam shaft driven from said driving shaft, a cam mounted thereon for effecting a relative movement between the tool and blank toward and from each other, means on said cam shaft

for operating said reversing mechanism and means for shifting said clutch mechanism comprising a pair of lugs adjustably mounted on said cam, a pair of rocking arms one of which is adapted to be engaged by one of said lugs and the other of which is adapted to be engaged by the other of said lugs during the rotation of said cam, each of said arms being provided with a toothed segmental portion adapted to mesh with the similar portion on the other arm, a rock shaft to which one of said arms is secured, and means actuated by movement of said rock shaft for shifting said clutch mechanism.

30. In a gear generating machine, a blank support, a tool, mechanism for effecting a relative rolling generating movement between the tool and blank, means for simultaneously imparting a continuous rotary motion to the blank, drive means for actuating said first named mechanism at a relatively fast speed and at a relatively slow speed, means for alternately connecting the fast and slow speed drives with said mechanism to actuate the same and means adjustable to control the operation of said last named means to predetermine the time of engagement of the fast and slow speed drives during the generating movement.

31. In a gear generating machine, a blank support, a tool, mechanism for effecting a relative rolling generating movement between the tool and blank in one direction and a relative rolling return movement in the opposite direction, means for simultaneously producing a continuous rotary motion of the blank during the rolling movement in either direction, drive means for actuating said mechanism at a relatively fast speed and at a relatively slow speed, means for alternately connecting the fast and slow speed drives with said first named mechanism to actuate the same and means adjustable to control the operation of said last named means to predetermine the time of engagement of the fast and slow speed drives during the cycle of operation of the machine.

32. In a gear generating machine, a blank support, a tool, mechanism for effecting a relative rolling generating movement between the tool and blank, means for simultaneously imparting a continuous rotary motion to the blank, means for effecting a relative depthwise feeding movement between the tool and blank during the first part of said generating motion and means for actuating said generating mechanism at a relatively fast speed during the feed motion and at a relatively slow speed thereafter while the gear is being cut.

33. In a gear generating machine, a blank support, a tool, mechanism for effecting a relative rolling generating movement between the tool and blank, means for simultaneously imparting a continuous rotary mo-

tion to the blank, means for producing a positive relative withdrawing movement between the tool and blank after the tooth surfaces of the blank have been completely generated and means for actuating said generating mechanism at a relatively slow speed during cutting and at a relatively fast speed during said withdrawing movement.

34. In a gear generating machine, a blank support, a tool, mechanism for effecting a relative rolling movement between the tool and blank, means for simultaneously imparting a continuous rotary motion to the blank, means for producing a relative depthwise feeding movement between the tool and blank during the first part of said rolling movement and for effecting a relative withdrawal movement between the tool and blank during the last part of said rolling movement and means for actuating said rolling mechanism at a relatively fast speed during the feed and withdrawing movements and at a relatively slow speed during actual cutting.

35. In a gear generating machine, a blank support, a tool, mechanism for effecting a relative rolling generating movement between the tool and blank in one direction and a relative rolling return movement in the opposite direction, means for simultaneously producing a continuous rotary motion of the blank during the rolling movement in either direction, means for imparting a relative depthwise feed movement between tool and blank during the first part of said rolling generating movement to move the tool and blank into engagement, means for driving the first named mechanism at a relatively fast speed and at a relatively slow speed, means shiftable to operatively connect either of said drives with said mechanism, and means adjustable to control the operation of said last named means to predetermine the time of engagement of the fast and slow speed drives during the cycle of operation of the machine.

36. In a gear generating machine, a blank support, a tool, mechanism for effecting a relative rolling generating movement between the tool and blank in one direction and a relative rolling return movement in the opposite direction, means for simultaneously producing a continuous rotary motion of the blank during the rolling movement in either direction, means for imparting a relative withdrawing movement during the latter part of said rolling generating movement, means for driving the first named mechanism at a relatively fast speed and at a relatively slow speed, means shiftable to operatively connect either of said drives with said mechanism and means adjustable to control the operation of said last named means to predetermine the time of engagement of the fast and slow speed drives during the cycle of operation of the machine.

37. In a gear generating machine, a blank

support, a tool, mechanism for effecting a relative rolling generating movement between the tool and blank in one direction and a relative rolling return movement between the tool and blank in the opposite direction, means for simultaneously producing a continuous rotary motion of the blank during the rolling movement in either direction, means acting automatically to commence a relative depthwise feed movement between the tool and blank during said rolling return movement and to complete said feed movement during the first part of said rolling generating movement, means for driving the first named mechanism at a relatively fast speed and at a relatively slow speed, means shiftable to operatively connect either of said drives with said mechanism and means adjustable to control the operation of said last named means to predetermine the time of engagement of the fast and slow speed drives during the cycle of operation of the machine.

38. In a gear generating machine, a blank support, a tool, mechanism for effecting a relative rolling generating movement between the tool and blank in one direction and a relative rolling return movement in the opposite direction, means for simultaneously producing a continuous rotary motion of the blank during the rolling movement in either direction, means acting automatically to commence a positive relative withdrawing movement between the tool and blank during the latter part of said rolling generating motion and to complete said relative withdrawing movement during the first part of said rolling return motion, means for driving the first named mechanism at a relatively fast speed and at a relatively slow speed, means shiftable to operatively connect either of said drives with said mechanism and means adjustable to control the operation of the last named means to predetermine the time of engagement of the fast and slow speed drives during the cycle of operation of the machine.

39. In a gear generating machine, a blank support, a tool, mechanism for effecting a relative rolling generating movement between the tool and blank in one direction and a relative rolling return movement in the opposite direction, means for simultaneously producing a continuous rotary motion of the blank during the rolling movement in either direction, means acting automatically to complete a relative depthwise feed movement between tool and blank and to commence a positive relative withdrawing movement between tool and blank during the first and latter parts of said rolling generating movement, respectively, means for driving the first named mechanism at a relatively fast speed and at a relatively slow speed, means shiftable to operatively connect either of said drives with said mechanism and means adjustable to control the operation of the last named means to pre-

determine the time of engagement of the fast and slow speed drives during the cycle of operation of the machine.

40. In a gear generating machine, a blank support, a tool, mechanism for effecting a relative rolling generating movement between the tool and blank in one direction and a relative rolling return movement in the opposite direction, means for simultaneously producing a continuous rotary motion of the blank during the rolling movement in either direction, means acting automatically to commence a positive relative withdrawing movement between the tool and blank during the latter part of said rolling generating motion, to complete said withdrawing movement during the first part of the rolling return motion, to commence a relative feeding movement during the latter part of the rolling return motion, and to complete said feeding movement during the first part of the rolling generating motion, means for driving the first named mechanism at a relatively fast speed and at a relatively slow speed, means shiftable to operatively connect either of said drives with said mechanism and means adjustable to control the operation of said last named means to predetermine the time of engagement of the fast and slow speed drives during the cycle of operation of the machine.

41. In a machine for generating gears, a blank support, a tool support, one of which is movable toward and from the other, a tool mounted on the tool support, a movable cradle upon which one of said supports is mounted, a train of gearing for imparting a rotary movement to the blank support and for actuating said cradle, comprising a drive shaft, a driven shaft operatively connected with the drive shaft thru reversing mechanism whereby the driven shaft rotates alternately in opposite directions and means connecting said reversible shaft with the blank support and cradle, means for simultaneously imparting to the blank a continuous indexing rotation, gearing for driving one element of said train at a relatively fast speed and at a relatively slow speed, means for actuating the reversing mechanism at predetermined points in the cycle of operation of the machine, means for effecting a relative movement between the tool and blank support toward and from each other at predetermined points in the cycle of operation of the machine, means shiftable to operatively connect either of said speed drives with said element, and means adjustable to control the operation of the last named means to predetermine the time of engagement of the fast and slow speed drives during the cycle of operation of the machine.

42. In a gear generating machine, a blank support, a tool, mechanism for effecting a relative rolling generating movement of the tool and blank in one direction and a relative

rolling return movement in the opposite direction, means acting automatically to impart a relative depthwise feed movement between the tool and blank during the first part of said rolling generating movement to move the tool and blank into engagement and means for actuating said first named mechanism at a relatively fast speed during the feed movement and at a relatively slow speed during actual cutting and again at a relatively fast speed during the rolling return movement.

43. In a gear generating machine, a blank support, a tool, mechanism for effecting a relative rolling generating movement between tool and blank in one direction and a relative rolling return movement in the opposite direction, means acting automatically to impart a relative withdrawing movement between the tool and blank during the latter part of said rolling generating movement and means for actuating the first named mechanism at a relatively slow speed during cutting and at a relatively fast speed during withdrawal and during the rolling return movement.

44. In a gear generating machine, a blank support, a tool, mechanism for effecting a relative rolling generating movement between tool and blank in one direction and a relative rolling return movement in the opposite direction, means acting automatically to commence a positive relative withdrawing movement between the tool and blank during the latter part of said rolling generating motion, to complete said withdrawing movement during the first part of the rolling return motion, to commence a relative feeding movement during the latter part of the rolling return motion and to complete said feeding movement during the first part of the rolling generating motion, and means for actuating said first named mechanism at a relatively fast speed during the feed and withdrawing motions and during said rolling return movement and at a relatively slow speed during actual cutting.

45. In a gear generating machine, a blank support, a tool, mechanism for effecting a relative rolling generating movement between the tool and blank in one direction and a relative rolling return movement in the opposite direction, means acting automatically to commence a positive relative withdrawing movement between the tool and blank during the latter part of said rolling generating motion, to complete said withdrawing movement during the first part of the rolling return motion, to commence a relative feeding movement during the latter part of the rolling return motion and to complete said feeding movement during the first part of the rolling generating motion, and means for actuating the first named mechanism at a relatively fast speed during the feed and withdrawing motions and during said rolling return movement and at a relatively slow speed during actual cutting.

speed and at a relatively slow speed, means shiftable to operatively connect either of said drives with said mechanism and means adjustable to control the operation of the last named means to predetermine the time of engagement of the fast and slow speed drives during the cycle of operation of the machine.
